UNITED STATES PATENT OFFICE.

ABRAHAM EGLY, OF GENEVA, INDIANA.

FENCE-POST.

No. 920,935.

Specification of Letters Patent.

Patented May 11, 1909.

Application filed January 19, 1909. Serial No. 473,053.

To all whom it may concern:

Be it known that I, ABRAHAM EGLY, citizen of the United States, residing at Geneva, in the county of Adams and State of Indiana, have invented certain new and useful Improvements in Fence-Posts, of which the following is a specification.

This invention relates to improvements in fence posts, more particularly to a corner 10 post especially adapted for a flood fence of wire used along the banks of a river or stream.

The object of the invention is to provide a simple and practical post of this character which will be strong, durable and comparatively inexpensive, and which may be readily folded over to a horizontal position so as to lie flat upon the ground when the banks of the river or stream, along which the fence extends, are overflowed, the folding of the post 20 and fence permitting ice, logs and other trash to float over the fence without injury to the same.

With the above and other objects in view the invention consists of the novel features of 25 construction and the combination and arrangement of parts hereinafter fully described and claimed and illustrated in the accompanying drawings in which:

Figure 1 is a side elevation of the improved 30 foldable post for a flood fence; Fig. 2 is a detail elevation of the other side of the post; Fig. 3 is a vertical section taken on line 3—3 in Fig. 2; and Fig. 4 is a vertical section taken on line 4—4 in Fig. 1.

In the drawings 1 denotes the body of the 35 post and 2 a diagonal brace for the same. These parts are preferably made of wood and rigidly connected to each other by metal straps 3 arranged upon their opposite sides, 40 one end of the brace being set in a recess in the post as shown. The post and brace are also united by a longitudinally extending and horizontally disposed tie-rod 4 which passes through said parts and has an adjusting nut 45 5 upon one of its ends.

The lower ends of the post and brace are pivotally mounted so that they can be folded over to a horizontal position as indicated in 50 dotted lines in Fig. 3. This mounting of the brace is preferably effected by securing to its angular lower end an angle metal plate or casting 6 from the vertical flange of which depends two integral lugs 7 formed in their bottom edges with U-shaped notches 12. 55 The latter are adapted to receive the upper or cross portions of U-shaped brackets 13, the

depending arms or ends of which are embedded in a cement block 14 or any other anchoring body or block. The construction just described enables either one of the brackets 13 to serve as a pivot or fulcrum for the brace while the casting 6 may readily swing into or out of engagement with the other of said brackets 13.

The hinge or pivotal mounting for the 60 post body is effected by bolting as at 15 or otherwise securing to one side of the lower portion of the same a channeled plate or casting 16. The latter is formed with two bearing ears 17 to receive a horizontal pivot rod 65 or bolt 18 extending through the eyes 19 of two eye bolts 20. The lower ends of these bolts or brackets 20 are embedded in a cement block or similar anchoring body 21 as indicated in dotted lines in Fig. 1. Upon 70 the side of the post, opposite that on which the channeled or flanged plate 16 is located, is secured by one of the bolts 15, a right angular bracket or strap 22. The horizontal arm 23 of this strap 22 is formed with an 75 opening to receive the screw threaded upper end of a pivotally mounted eye bolt 24. The eye of the bolt 24 rotates upon a U-shaped bracket 25 having the ends of its arms embedded in the block 21. Upon the bolt 24 80 above and below the arm 23 of the angle strap or plate 22 are adjusting and retaining nuts 26 by means of which the post may be maintained in a perpendicular position. When the upper nut 26 is removed from its 85 bolt, the post and its brace may be swung over flat upon the ground or to a horizontal position, as indicated in dotted lines in Fig. 3. The post swings in the direction of the side on which the plate 16 is located, but 90 said plate may be placed on the other side of the post, thereby permitting the latter to be mounted for swinging movement in either direction without the necessity of having 95 different fittings.

100 My improved post is especially adapted for the corner or end of a flood fence but it may be used at other points in the fence.

The fence (not illustrated) may be of wire or of any other form, material and construction.

105 The blocks or bases 14 and 21, which are preferably made of cement, may be pieces of natural stone or anchoring bodies of any other description. They may be of any size 110 and shape and embedded in the ground to any depth according to its character.

From the foregoing it will be seen that the invention provides an exceedingly simple and practical fence post for a flood fence located along the banks of a stream or river which overflows its banks. The pivotal mounting of the post and fence enables them to be dropped to a horizontal position flat upon the ground during flood times so that ice, logs and trash will float over them without injuring them, or piling up against them.

Various changes in the form, proportion and minor details of construction may be made within the scope of the appended 15 claims.

Having thus described the invention, what I claim is:

1. The combination of a base, a foldable post arranged above and spaced from the 20 base, pivot supporting eyes upon the base, a pivot in said eyes, a hinge plate secured to one side of the post and rotatable upon said pivot, an angle bracket secured to the other side of the post and having an apertured 25 end, a bolt pivoted to the base and projecting upwardly through the aperture in the end of said bracket, and nuts upon the

threaded portion of the bolt above and below said apertured end of the bracket whereby the post may be adjusted and maintained 30 in a perpendicular position.

2. The combination of the base, a foldable post arranged above and spaced from the base, pivot supporting eyes upon the base, a pivot in said eyes, a hinge plate secured to one side of the post and rotatable upon said pivot, an angle bracket secured to the other side of the post and having an apertured 40 end, a bolt pivoted to the base and projecting upwardly through the aperture in the end of said bracket, and nuts upon the threaded portion of the bolt above and below the apertured end of the bracket, and a diagonal brace fixed to one side of the post and projecting downwardly therefrom, 45 the lower end of the brace being hingedly mounted whereby it may fold with the post.

In testimony whereof I affix my signature in presence of two witnesses.

ABRAHAM EGLY.
